Ackture Ultrasonic UV Cleaner, available in Amazon.com, customer review oldest date Apr. 22, 2024 [online], [site visited Jan. 23, 2024], Available from the internet URL: <https://www.amazon.com/Ultrasonic-Dentures-Retainer-Toothbrush-Professional/dp/B0CP1QXD99/> (Year: 2024).*

Primary Examiner — Joshua Kading*Assistant Examiner* — Jenny lou M Binas(57) **CLAIM**

The ornamental design for an ultrasonic cleaning machine, as shown and described.

DESCRIPTION

FIG. 1 is a top perspective view of an ultrasonic cleaning machine showing my new design.

FIG. 2 is a bottom perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof; and,

FIG. 9 is a perspective view of the ultrasonic cleaning machine showing the lid open.

The broken lines illustrate portions of the ultrasonic cleaning machine that form no part of the claimed design.
